Primary Examiner — Mark A Goodwin(74) *Attorney, Agent, or Firm* — Global IP Counselors,
LLP(57) **CLAIM**

The ornamental design for a bicycle lock holder, as shown and described.

DESCRIPTION

FIG. 1 is a front view of a bicycle lock holder in accordance with our new design showing the cross bar in a closed position;

FIG. 2 is a left side view thereof;

FIG. 3 is a right side view thereof;

FIG. 4 is a rear view thereof;

FIG. 5 is a top view thereof;

FIG. 6 is a bottom view thereof;

FIG. 7 is a front perspective view thereof with the cross bar in a closed position;

FIG. 8 is a rear perspective view thereof with the cross bar in a closed position;

FIG. 9 is a front perspective view thereof with the cross bar in an opened position; and,

FIG. 10 is a top view thereof with the cross bar in an opened position.

The contour lines depict illustration only, and form no part of the claimed design.
